UNITED STATES PATENT OFFICE.

GEORGE W. WILSON, OF CAYUGA, INDIANA, ASSIGNOR OF ONE-THIRD TO FRANK M. MALONE
AND ONE-THIRD TO DANIEL WILSON, OF CAYUGA, INDIANA.

ENGINE.

No. 876,890.

Specification of Letters Patent.

Patented Jan. 14, 1908.

Application filed April 20, 1907. Serial No. 369,382.

To all whom it may concern:

Be it known that I, GEORGE W. WILSON, a citizen of the United States, residing at Cayuga, in the county of Vermilion and State of Indiana, have invented certain new and useful Improvements in Explosive-Engines, of which the following is a specification.

My invention relates more particularly to new and useful mechanism for regulating the speed of explosive engines now in common use, such as gas, gasolene or oil engines, and has for its object the production of a mechanism of the character described whereby the speed of the engine may be changed, regulated and controlled at will while running without having to stop the engine as has been necessary heretofore and to this end my invention consists in the peculiar construction, combination and arrangement of the several parts as will be more fully set forth hereinafter.

Referring to the accompanying drawings forming a part of this specification, in which like letters and numerals of reference indicate corresponding parts throughout the several views; Figure 1 is an elevation of the main portion of an explosive engine showing my invention applied to the same. Fig. 2 is a detail plan of my invention entire. Fig. 3 is a detail view of the same obtained from the direction indicated by the arrow A, Fig. 2. Fig. 4 is an enlarged vertical section upon the line, *m*, *n*, Fig. 2. Fig. 5 is an enlarged detail of the tension block and thumb-wheel.

Before detailing the merits of my invention further it will be expedient to observe here that I have shown only the main portion of an explosive engine provided with a well known governor for the reason that it is unnecessary to show and describe the other operating parts to disclose the merits and operation of my improvement which is intended for use upon any well known form of explosive engines in common use. Also it will be readily seen that the operating parts of an explosive engine may widely differ in form and operation without materially interfering with the merits, operation and adoption of my invention in connection with the same. By preference for an illustrative purpose I have shown an explosive engine of the well known vertical type in which the governor is mounted upon the gear-wheel instead of upon the fly-wheel as is practiced in the larger type.

A represents the main portion of an explosive engine, B the fly-wheel, C the base, and D the governor, all of which are of well known construction.

E and numerals represent the various parts of my improvement. The governor comprises the weights D, the elbow-levers D' and the sleeve D². The elbow-levers D' are fulcrumed upon the gear-wheel at the points D³ and have their inner ends set in an annular groove of the sleeve D² and their outer ends rigidly secured to the weights D.

The operation of the governor has been controlled heretofore by the provision of an ordinary spiral spring secured by an adjustable link or a similar take-up device to and between the weights D and of such well known constructions that illustration and description is deemed unnecessary. The regulation of the operation of the governor by all known means secured to and between the weights D for the purpose of regulating and changing the speed of an explosive engine made it necessary heretofore to stop the engine for allowing such means between the weights D to be manipulated and adjusted to obtain the desired operation of the governor for producing the speed desired in the engine. The sleeve D² which is freely mounted upon the gear-shaft F has a longitudinal movement thereon which is produced by the operation of the governor for a well known purpose. The gear-wheel F' which is rigidly secured upon the gear-shaft F is driven by the gear-wheel F² securely mounted upon the main drive-shaft F³.

The objectionable features to such old and well known means of regulating the operation of the governor is the loss of time occasioned by having to stop the engine for making the necessary manipulation and adjustment for producing the desired speed and the intervals of irregular explosions caused, more commonly termed "sputtering", in the running of the engine and it will now be more readily apparent that the particular object of my invention is to avoid such old and well known means and to obviate these objections.

In the attainment of my object means heretofore secured to and between the governor weights D for regulating the operation of the governor, are in my invention entirely discarded.

E represents the main frame of my inven-

tion, E¹ the angle-lever, E² the geared hand-wheel, E³ the threaded thumb-wheel, E⁴ the grooved tension block, E⁵ the downstanding tension-spring, E⁶ the tension pin, E⁷ the tension arm, and E⁸ the friction roller which operates against the inner, annular collar of the governor sleeve D² for affecting, as may be determined, its longitudinal movement upon the gear-shaft F for the well known purpose of properly timing the other necessary operating parts of an explosive engine. The main frame E is fulcrumed to the main portion A of the engine by a suitable through-pin and nut E⁹ and is provided with a link-like head E¹⁰, a downstanding arm E¹¹, and a downstanding slotted portion E¹². The link-like head E¹⁰ has an elongated slot E¹³ provided with a cogged inner wall E¹⁴ which meshes with the cogged gear of the hand-wheel E². The hand-wheel E² has an instanding collar E¹⁵ provided with a cogged gear E¹⁶ at its inner end which inserts into the elongated slot E¹³ and meshes with its cogged inner wall E¹⁴ and has a suitable central opening for the through-pin E¹⁷ of the main portion A upon which it is rigidly secured by the nut E¹⁸. By manipulating the hand-wheel E² and the nut E¹⁸ the main frame E may be tilted, set and secured as desired. The downstanding portion E¹² has a long opening E¹⁹ for the reception of the grooved tension block E⁴. The tension block E⁴ has a pair of parallel grooves E²⁰ for the reception of the side portions of the downstanding portion E¹² of the main frame and an annular groove E²¹ for the reception of the forked end of the angle-lever E¹. The thumb-wheel E³ has a long threaded stem E²² which passes through a suitable threaded opening in the block E⁴ and has a lock-nut E²³ upon the threaded stem adjacent the tension block for rigidly securing it. The end of the stem E²² operates against the tension spring E⁵ and by manipulating the thumb-wheel and the lock-nut the stem E²² may be minutely adjusted and rigidly set against the tension spring E⁵ for procuring the most accurate adjustment. The angle-lever E¹ is fulcrumed to the downstanding arm E¹¹ at the point E²⁴ and is provided with a finger-hold E²⁵, an instanding pin E²⁶ and a forked end E²⁷. The pin E²⁶ inserts in suitable openings E²⁸ in the main frame and the forked end E²⁷ operates in the annular groove E²¹ of the tension block. By manipulating the finger-hold E²⁵ the angle-lever E¹ may be oscillated from its position shown to any position desired over the openings E²⁸ and the pin E²⁶ set therein and by which operation the speed of the engine is changed from the lowest to the highest or to any intermediate speed desired while the engine is running. The tension spring E⁵ has a suitable opening at its upper end for the reception of the threaded projection of the tension pin E⁶ and is rigidly secured thereon by the nut E²⁹.

The tension pin E⁶ is freely mounted in a suitable opening in the main portion A of the engine and has its inner threaded projection inserted through a suitable opening in the lower part of the upstanding arm E⁷ which is rigidly secured thereon by the nut E³⁰. The tension arm E⁷ at its upper end is provided with a rigid instanding pin E³¹ which passes through a suitable opening in the friction roller E⁸ which is mounted freely thereon, adjacent the inner annular collar of the governor sleeve D².

It will readily be seen that by manipulating the hand-wheel E² and nut E¹⁸ and the thumb-wheel E³ and lock-nut E²³ that the adjustment of the pressure of the friction roller E⁸ against the inner annular collar of the governor sleeve D² may be attained and maintained with great exactness for the well known purpose of properly timing the operations of the other necessary operating parts of an explosive engine for establishing the limits of its maximum and minimum speed. It will further be apparent that by manipulating the angle-lever E¹ by the finger-hold E²⁵ that five changes may be obtained in the speed of the engine which number I have found ample for all practical purposes. There may be obtained as many changes in the speed of the engine as there are openings E²⁸ provided in the main frame E for the pin E²⁶ of the angle-lever. The correct objective to be sought in the adjustment of my invention is to obtain and maintain a tension or pressure through the friction roller E⁸ against the longitudinal movement of the governor sleeve D² upon the gear shaft F which will provide the lowest or minimum speed upon which the engine can run when the angle-lever E¹ is positioned as shown in Fig. 1 and when the angle-lever E¹ is oscillated to the opposite limit of its travel the highest or maximum speed is provided to which the engine may be subjected.

The advantages of my invention are apparent to every one skilled in the art to which it pertains, such as economy of time and the saving of fuel. It further obviates the objectionable "sputtering" and the necessity of friction clutches when used for various purposes.

Having thus fully described my invention and set forth the operation and advantages thereof what I claim as new and desire to secure by Letters Patent is:—

1. In a speed regulator for explosive engines, the same comprising a main frame suitably fulcrumed to the main portion of the engine and having a link-like head provided with an elongated slot and a cogged inner wall, a downstanding arm, a downstanding portion provided with an elongated slot, and a series of openings between the fulcrum point and the link-like head; a grooved tension block mounted freely in the elongated

- slot of the downstanding portion and provided with an annular groove and a threaded opening; a tension spring adjacent the downstanding portion of the main frame rigidly secured at its upper end to the tension pin; a tension pin mounted freely in a suitable opening in the main frame of the engine adjacent to the gear shaft; a tension arm rigidly secured upon the inner projection of the 5 tension pin and provided with an instanding pin at its upper end; a friction roller mounted freely upon the instanding pin of the tension arm; a thumb-wheel having a threaded stem mounted in a suitable opening in the tension 10 block for manipulating its point against the tension spring and provided with a lock-nut for rigidly securing it; a hand-wheel mounted freely upon the through-pin of the main portion of the engine and provided with an in- 15 standing collar having a cogged gear at its inner end which meshes with the cogged inner wall of the elongated slot of the link-like head and a lock-nut upon the through-pin of the main portion of the engine for rigidly 20 securing it; and an angle-lever fulcrumed at the lower end of the downstanding arm of the main frame and provided with a forked end which operates in the annular groove of the tension block, an instanding pin for insertion 25 in the openings of the main frame, and an outstanding finger-hold at its upper end; and all for adjusting, regulating and changing the speed of the engine in the manner and for the purposes set forth, substantially as specified. 30
- 35 2. In a speed regulator for explosive engines, the same comprising a tension pin mounted freely in a suitable opening in the main portion of an explosive engine adjacent the gear shaft and the governor sleeve; a tension arm rigidly secured at its inner end upon the inner projection of the tension pin 40
- and provided at its outer end with a rigid instanding pin having a friction roller mounted freely thereon and operating against the inner annular collar of the governor sleeve; 45 a tension spring rigidly secured at its inner end to the outer projection of the tension pin; and suitable means adjacent and operating against the tension spring for manipulating the same for the purpose of adjusting, 50 regulating and changing the speed of the engine, substantially as specified.
3. In a speed regulator for explosive engines, the same comprising the governor sleeve mounted freely upon the revolute 55 gear or drive shaft of the engine; the revolute gear or fly wheel rigidly secured upon the revolute gear or drive shaft and provided with suitable means for imparting a longitudinal movement to the governor sleeve; a 60 tension pin mounted freely in a suitable opening in the main portion of the engine adjacent the gear shaft and the governor sleeve; a tension arm rigidly secured at its inner end upon the inner projection of the 65 tension pin and provided at its outer end with a rigid instanding pin having a friction roller mounted freely thereon and operating against the inner annular collar of the governor sleeve; a tension spring rigidly secured 70 at its inner end upon the outer projection of the tension pin; and suitable means adjacent and operating against the tension spring for manipulating the same for the purpose of adjusting, regulating and changing the speed 75 of the engine at will, substantially as specified.

GEORGE W. WILSON.
